UNITED STATES PATENT OFFICE

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE

BUTTONHOLE SEWING MACHINE

Application filed September 1, 1927. Serial No. 216,868.

This invention relates to buttonhole sewing machines and has for its principal object to provide a buttonhole sewing machine which is capable of cutting the buttonhole slit either before or after the sewing operation.

In sewing buttonholes in some kinds of cloth it is desirable to cut the slit before the buttonhole stitches are sewed while in other cloths it may be most desirable to cut the buttonhole slit after the stitching has been completed. Usually buttonhole sewing machines are constructed so that they will cut the slit only either before the sewing operation or after the sewing operation and consequently in ordering a machine it is usual for the customer to specify whether the machine is to be of the kind which will cut the slit before the sewing operation or of the kind which will cut the slit after the sewing operation.

My invention provides novel means by which a buttonhole sewing machine may be adjusted to cut the buttonhole either before or after the sewing operation and hence a machine embodying my improvements is adapted for sewing buttonholes in the kind of work which requires the buttonhole slit to be cut before the sewing operation and also in the kind of work which requires the buttonhole to be cut after the sewing operation.

In these buttonhole sewing machines the buttonhole cutter is usually actuated by a cam projection formed on the main cam of the machine which makes one complete rotation during each sewing cycle.

In carrying out my invention I provide a construction by which the sewing machine may be brought to rest at the end of each sewing cycle either just before the cutting cam actuates the buttonhole cutter or just after it has actuated said cutter. If the sewing machine is brought to rest with the cutting cam in the first position then when the machine is started again for sewing the next buttonhole the cutting cam will actuate the cutter before the sewing begins. While if the machine is stopped in the second position just after the cam has actuated the cutter

then the cutting cam will have to make a substantially complete rotation before it comes into position to actuate the cutter and during this rotation the sewing on the buttonhole will have been completed, the cutting **55** of the slit thus being done after the sewing operation.

In order to give an understanding of my invention I have illustrated in the drawings **60** a selected embodiment thereof which will now be described after which the novel features will be pointed out in the appended claims.

Fig. 1 is a side view of a sewing machine **65** having my improvements applied thereto;

Fig. 2 is an under side view of the bed;

Fig. 3 is a fragmentary detail view;

Figs. 4, 5 and 6 are fragmentary views **70** showing the means for controlling the time of bringing the machine to rest at the end of each sewing cycle; Figs. 4 and 5 illustrating the parts in adjusted position for effecting the cutting of the buttonhole after the sewing operation has been completed while Fig. 6 shows the parts in position for **75** effecting the cutting of the buttonhole before the sewing operation begins;

Figs. 7 and 8 are fragmentary views illustrating the different stopping positions of **80** the main cam at the time the machine is brought to rest, Fig. 7 showing the stopping position when the buttonhole is cut after the sewing operation and Fig. 8 showing the stopping position when the buttonhole is cut before the sewing operation; **85**

Figs. 9, 10, 11 and 12 are fragmentary views illustrating the operation of the stop-controlling mechanism.

Fig. 13 is a fragmentary view of the stop-**90**ping position of the main cam when the buttonhole is to be cut before the sewing operation.

In the drawings 1 indicates the bed portion of the sewing machine and 2 the frame **95** which carries the stitch-forming mechanism, the latter comprising the usual needle 3 carried by a needle bar 4 which is mounted for vertical reciprocation in the overhanging arm 5 of the frame 2, and also comprising under thread handling mechanism which is **100**

carried by a turret 6 situated beneath the bed frame and mounted to turn in suitable bearings 7 carried by the portion 8 of the frame 2.

The work is held in position on the bed 1 by usual work clamps 9, the latter being supported by clamp arms 10 which are pivoted to the bed frame at 11. The means for opening and closing the clamps 9 are similar to that illustrated in Patent No. 713,764, dated November 18, 1902. The clamp arm 10 is extended below the pivot 11 and is provided with a lip 12 adapted to engage a lip 13 on a swinging frame 14 which is pivoted to the bed at 15. This frame 14 has a bracket arm 16 depending therefrom, to the lower end of which is pivoted one end of a toggle member 17, the latter having pivotal connection at 18 to the lower end of the co-operating toggle member 19 which is pivoted to the bed 1 at 20. The bracket arm 16 is acted on by a spring 21 which normally holds the toggle 17, 19 in broken position as shown in Fig. 1. When the toggle is straightened the bracket arm 16 will be forced downwardly since the upper pivot 20 of the toggle is stationary in the bed frame 1. Such downward movement of the bracket arm 16 will swing the arm 14 downwardly and thus cause the lip 13 to engage the lip 12, this resulting in closing the work clamps.

The straightening of the toggle member 17, 19 is secured in usual way from the main cam 22 of the machine which is mounted in the cam housing 23 that is rigid with the frame 2. This cam housing has a lever arm 24 pivoted thereto at 25, the front end of the arm overlying and being adapted to engage an arm 26 rigid with the toggle member 17. The lever arm 24 carries a roll 27 which is adapted to be engaged by a cam projection 28 on the under side of the main cam 22, the engagement of the cam projection 28 with the roll moving the lever 24 downwardly and causing it to act against the arm 26 thereby straightening the toggle all as shown in the above-mentioned patent.

The button hole cutter is shown at 280 and it is carried by a cutter arm 29 pivoted to the frame 2 at 30 and said cutter is given its cutting movement by a cam projection 31 formed on the top of the main cam 22, said projection being adapted to engage the tail 32 of the cutter arm as the cam rotates. The cutter is normally held in its raised position by a spring 33.

The main cam 22 is rotated from a drive shaft 34, the latter having spiral gear teeth 35 thereon that mesh with co-operating gear teeth 60 on the periphery of the cam as usual. When the sewing machine is first started by depression of the starting lever 36 the shaft 34 is automatically coupled to a driving pulley 37 and the cam 22 derives its initial turning movement from the driving pulley 37.

During this initial movement the parts are brought from starting position shown in full lines Fig. 1 to stitching position shown in dotted lines and it is during this initial movement of the cam 22 that the clamps are closed. 70

When the stitching position has been reached the stitch-forming mechanism is set in operation and the pulley 37 is automatically disengaged from the shaft 34, the cam 22 thereafter being turned by means actuated by the driving shaft for the stitch-forming mechanism all as usual in sewing machines of this type. During the stitching on the buttonhole the frame 2 is moved back and forth on the bed 1 by means of a feed cam groove 38 in the upper face of the main cam 22, said cam groove receiving a stud 39 rigid with the bed frame 1, this being a construction commonly used in buttonhole sewing machines of this type. When the stitching on the buttonhole 80 has been completed the stitch-forming mechanism is brought to rest and the driving pulley 37 is again clutched to the shaft 34 so that the final movement of the main cam 22 is derived from the pulley 37. 90

The means controlling the operation of clutching the pulley 37 to and unclutching it from the shaft 34 is similar to that illustrated in Patent No. 655,637, August 7, 1900. The pulley 37 is slidably mounted on the shaft 34 95 and is provided with a clutch dog 40 adapted to engage a co-operating dog 41 on an arm 42 rigid with the shaft 34. The movement of the pulley longitudinally of the shaft is controlled by a clutch-controlling lever 43 which is pivoted to the cam casing at 44 and is provided with a forked portion 45 engaging in a groove in a hub 46 of the pulley 37. This controlling lever 43 is acted on by a spring 47 which normally tends to move the pulley into 105 its clutching engagement with the shaft.

The pulley is held in its unclutched condition shown in Fig. 2 by a lever 48 which is pivoted at 49 to the bed 1, said lever having a pin 50 at one end which engages the lever 43 and being normally held in the position shown in Fig. 2 by the lower end 59 of the starting lever 36. When the starting lever is depressed the lower end thereof is disengaged from the lever 48 and as the latter is released the spring 47 will operate to shift the pulley 37 into clutching engagement with the shaft 34. 110

The parts thus far described are or may be all as usual in devices of this sort and as shown in the various patents above referred to and form no part of the present invention, which as stated above relates to a construction by which the buttonhole cutter may be operated either before or after the sewing operation. This end is accomplished by means which controls the stopping position of the main cam 22. If the buttonhole slit is to be cut before the sewing operation then this cam 22 will be stopped with the cutting 120 125 130

cam 31 having the relative position to the tail 32 of the cutting lever shown in Fig. 13 while if the buttonhole slit is to be cut after the sewing operation the stopping position of the cam will be that shown in full lines in Fig. 1.

Assuming that the parts are adjusted so that the stopping position of the cam is as shown in Fig. 13 and that the cam has the direction of rotation indicated by the arrow it will be apparent that as the cam 22 starts to rotate the cutting cam 31 will act against the tail 32 during the initial movement of the cam and thus before the stitch-forming mechanism is set in operation. This will result in cutting the buttonhole slit before the stitching is begun. On the other hand, if the stopping position of the main cam is that shown in full lines in Fig. 1 then when the cam starts in operation the cutting cam 31 will move away from the tail 32 thus leaving the cutter 280 idle and said cutting cam 31 will not be brought into position to actuate the cutter until the main cam 22 has nearly completed its revolution. With this adjustment of parts it is obvious that the cutting of the buttonhole slit will occur after the stitching has been completed.

The mechanism employed for effecting a cutting of the buttonhole before the stitching is begun is similar to that shown in the above-mentioned Patent No. 713,764.

As stated above if the buttonhole is to be cut before the stitching operation the stopping position of the cam 22 will be that shown in Fig. 13 and the cutting cam 31 will occupy a position directly in front of the tail 32, a position indicated by dotted lines in Fig. 1. When the machine is started the cam 28 depresses the arm 24, straightens the toggle 17, 19 and closes the clamps as above described and immediately thereafter the cutting cam 31 acts on the tail 32 of the lever 29 and actuates the buttonhole cutter 280. As soon as the cam 28 has passed the roll 27 the lever arm 24 will be raised by the spring 51, the roll 27 at this time resting against a cam track 52 on the cam 22. During the sewing on the first side of the buttonhole the frame 2 is moving to the left Fig. 1 and as the sewing on the second side of the buttonhole progresses the frame 2 moves to the right and during this movement the end 53 of the lever arm 24 engages the lug 54 of the toggle member 17 as shown by dotted lines Fig. 6 and during further movement of the frame 2 and arm 24 the toggle will be broken thus unclamping the work.

The breaking of the toggle is accompanied by the disconnecting of the pulley 37 from the shaft 34, thus bringing the machine to rest. To do this I have provided a finger 55 pivoted at 56 to a lug on the end of the lever 48, the end of said finger resting on the central joint of the toggle 17, 19 and being retained from lateral movement by a guard

flange 57. By reason of this construction the finger 55 will have an up and down swinging movement as the toggle 17, 19 is broken or straightened. The straightening of the toggle lever obviously lowers the central pivot thereof and at the same time swings said central pivot to the left Figs. 1, 4, 5, and 6. The finger 55 is curved slightly so that this swinging of the central pivot of the toggle lever to the left allows the finger 55 to move downwardly from the position shown in Fig. 1 to that shown in Fig. 4. On the other hand, the breaking of the toggle causes the finger 55 to be elevated. This finger 55 is provided with an upstanding wedge-shaped member 58 which during the upward movement of said finger from the position shown in Fig. 6 to that shown in Fig. 1 is forced between the tail 59 of the starting lever 36 and the portion 60 of the lever 48. The tail 59 of the starting lever is prevented from lateral movement and thus the wedging action of the member 58 turns the lever 48 into the position shown in Fig. 2 and thereby disconnects the pulley 37 from the shaft 34. This action of the wedge 58 is illustrated in Figs. 9 and 12. Fig. 12 shows the wedge in its lowered position corresponding to Fig. 6 and as the lever 55 is moved upwardly into the position shown in Fig. 1 the wedge 58 crowds between the tail 59 and the part 60 and thus moves the part 60 to the left, Figs. 9 and 12. When the starting lever 36 is depressed the tail 59 is swung out of engagement with the upstanding wedge 58 thus withdrawing the restraining force which holds the part 60 in the position shown in Fig. 9 and allowing the lever 48 to swing so that the spring 47 can shift the pulley into clutching engagement with the shaft.

Fig. 10 illustrates the relative position of the part 60 and wedge member 58 after the starting lever has been actuated and Fig. 11 shows the relative position of the parts after the toggle has been straightened to close the clamps.

The parts are so designed that when the toggle lever 19, 17 is broken by the action of the lever arm 24 as shown in Fig. 6 the machine will be brought to rest with the main cam 22 in the position shown in Fig. 8 and with the cutting cam 31 in the position relative to the tail 32 illustrated in Fig. 13 and in dotted lines in Fig. 1.

If it is desired to cut the buttonhole after the stitching has been completed the lever arm 24 will be rendered inoperative for breaking the toggle 17, 19 and thus bringing the machine to rest and this operation of breaking the toggle will be delayed until after the cutting cam 31 has passed by the tail 32 of the cutting lever and thereby has actuated the cutter 280.

To accomplish this I have provided the following mechanism. 61 indicates a swing-

ing member which is pivoted at 62 to the under side of the casing 23 which encloses the main cam 22. The swinging member 61 has an arm 64 pivoted thereto at 65 and said arm carries at its end a bunter 66. The pivotal connection between the arm 64 and the swinging member 61 permits the arm to be moved either into operative position shown in Fig. 2 or into inoperative position shown in Fig. 3. The arm 64 may be clamped in either position by a clamping screw 67 which extends through a slot 68 formed in the arm 64. When the arm 64 is in its operative position shown in Fig. 2 the bunter 66 overlies the end 53 of the lever arm 24 and holds said lever arm slightly depressed from its normal position, in which depressed position the line of travel of the end of the lever arm is below the projection 54. Consequently when the lever arm is thus held depressed by the bunter 66 the end 53 of said lever arm will pass beneath the projection 54 during the final movement of the frame 2 by which the parts are carried from stitching to stopping position. Consequently instead of the toggle 17, 19 being broken when the end 53 of the lever comes in line with the end of the projection 54 said toggle will remain straightened and, of course, the cam 22 will continue to be turned by the driving pulley 37. During such continued turning movement of the cam the cutting cam 31 engages the tail 32 of the cutting lever and actuates the latter, this occurring after the stitching has been completed. In other words, during this further movement the cam 22 is moved from the position shown in Fig. 8 to that shown in Fig. 7 and the cutting cam is moved from the dotted line to the full line position Fig. 1. As soon as the cutter has been actuated the toggle is then broken causing the pulley 37 to be unclutched from the shaft and the machine to be brought to rest. For accomplishing this I propose to employ means actuated by the turret-rotating means.

It will be understood by those familiar with sewing machines of this type that the turret is given a half rotation after one side of the buttonhole has been completed to sew around the end of the buttonhole and is given another half rotation at the end of the buttonhole, and that at some point between the finishing of the stitching on one buttonhole and the starting of the stitching on the next buttonhole the turret is given a reverse rotation to bring it back to its initial position.

I propose to utilize the movement of the turret-rotating means in giving the turret this reverse rotation to break the toggle 17, 19 and thus stop the machine with the cam in the position shown in Fig. 7 and after the buttonhole cutter has been actuated. The means for rotating the turret is that commonly employed in machines of this type and comprises a lever 69 pivoted to the cam casing

at 70 and actuated by a groove in the cam 22, said lever being connected by a link 71 to an arm 72 fast on a vertical shaft 73, the latter having gear segments 74, 75 thereon which mesh with gears 76, 77 on the turret and on the needle bar carrier respectively. When the sewing is completed the turret-rotating mechanism is in the dotted line position Fig. 2 and after the sewing has been completed and while the parts are moving to stopping position said turret-rotating mechanism is moved into the full line position Fig. 2 thereby to give the turret a reverse rotation into its initial position. During this swinging movement of the arm 72 from the dotted to the full line position Fig. 2 it engages a projection 78 on the swinging member 61 and swings said member from the dotted to the full line position. During this swinging movement of the member 61 the bunter 66 engages the projection 54 as shown in Fig. 5 and breaks the toggle, 17, 19 thereby bringing the machine to rest. This occurs directly after the buttonhole cutter has been actuated and when the main cam is in the position shown in Fig. 7.

When the buttonhole is to be cut before the sewing operation the bunter 66 is moved into inoperative position shown in Fig. 3. This is done by loosening the clamping screw 67 and swinging the arm 64 backwardly as far as the slot 68 will permit and then tightening the clamping screw. When in this position the bunter 66 is situated inside of the arm 53 and out of line laterally with the projection 54. When the arm 64 is thus in the inoperative position the device will operate as usual to cut the buttonhole slit before the sewing operation begins.

Inasmuch as the main cam 22 is brought to rest in a different position when the cutting is to be done before the buttonhole stitching than it is when the cutting is to be done after the buttonhole has been completed and inasmuch as it is necessary to straighten the toggle 17, 19 when the machine is set in operation, I have provided the cam 22 with two cam projections each adapted to actuate the lever arm 24. One of these cam projections 28 has been referred to. The other is shown at 28a.

These two cam projections 28, 28a are so positioned that one of them will be in the proper location to actuate the lever arm 24 to straighten the toggle and thereby lower the clamps when the machine is set for cutting the buttonhole before the stitching operation, and the other cam projection will be so positioned that it will be operative to actuate the arm 24 and thus lower the clamps as the machine is started when the parts are adjusted for cutting the buttonhole after the stitching operation.

The arm 24 will thus be depressed twice during each rotation of the cam 22 but only

one of these depressing movements will be operative, the other being an idle movement.

I claim:

1. In a buttonhole sewing machine, the combination with stitch-forming mechanism, of a buttonhole cutter, a controlling cam which rotates once during each buttonhole-forming cycle, the stitch-forming mechanism being operated during a part of each rotation and the cutter being actuated during another part of said rotation, and means to bring the cam to rest either just after the cutter is actuated for one buttonhole-forming cycle or just before it is actuated for the next 15 succeeding buttonhole-forming cycle.

2. In a buttonhole sewing machine, the combination with stitch-forming mechanism, of a buttonhole cutter, a main cam which rotates once during each buttonhole-forming cycle, the stitch-forming mechanism being operated during a part of each rotation, a cutter-actuating cam on the main cam, and means whereby said cam may operate the cutter either before or after the stitching operation.

25 3. In a buttonhole sewing machine, the combination with stitch-forming mechanism, of work clamps, a buttonhole cutter, a main cam which rotates once during each buttonhole-forming cycle, the stitch-forming mechanism being operated during a part of each rotation, a cutter-actuating cam on the main cam, means whereby said cam may operate the cutter either before or after the stitching operation, and means for closing the work 30 clamps during the initial movement of the main cam.

4. In a buttonhole sewing machine, the combination with stitch-forming mechanism, of a buttonhole cutter, work clamps, a toggle 40 device for closing said clamps, a main cam which rotates once during each buttonhole-forming cycle, the stitch-forming mechanism being operated during a part of each rotation of said cam and the cutter being actuated at 45 a predetermined point in each rotation, means to release the work clamps and bring the cam to rest either just after the cutter is actuated in one buttonhole-forming cycle or just before it is actuated in the next buttonhole-forming cycle, and means operative during 50 the initial movement of the cam to close the clamps.

5. In a buttonhole sewing machine, the combination with stitch-forming mechanism, 55 of a buttonhole cutter, a main cam which rotates once during each buttonhole-forming cycle, a cam projection on the main cam by which the cutter is actuated, work clamps, means for closing the work clamps during the initial movement of the main cam, and means to release the clamps and bring the cam to rest either just before or just after the cam projection actuates the cutter.

6. In a buttonhole sewing machine, the 60 combination with stitch-forming mechanism

including a rotary turret, of a buttonhole cutter, work clamps, a main cam, means operated thereby to close the work clamps before the stitching operation and to actuate the cutter after the stitching operation, a swinging arm by which the turret is rotated, means actuated by the main cam to give said arm its operative movement, and means actuated by said arm to release the work clamps after the buttonhole has been cut.

7. In a buttonhole sewing machine, the combination with stitch-forming mechanism including a rotary turret, of work-holding means including work clamps, said stitch-forming mechanism and work-holding means having a relative movement, a main cam by which the relative movement is produced and which makes one rotation during each buttonhole-forming cycle, a buttonhole cutter, means actuated by the main cam at a predetermined point in each rotation to operate the cutter, turret-rotating means actuated by the main cam, means for releasing the clamps and bringing the cam to rest either by said relative movement between the stitch-forming mechanism and work-holding means or by the turret-rotating means.

8. In a buttonhole sewing machine, the combination with stitch-forming mechanism including a rotary turret, of work-holding means including work clamps, said work-holding means and stitch-forming mechanism having a relative movement, a main cam for producing such relative movement, which main cam makes one rotation during each buttonhole-forming cycle, a buttonhole cutter, means actuated by the main cam at a predetermined point in its rotation to actuate said cutter, means rendered operative by such relative movement to release the clamps just before the main cam reaches its cutter-actuating position, other means actuated by the turret-rotating means to release the work clamps just after the main cam has reached cutter-actuating position, and means whereby either clamp-releasing means may be rendered operative at the will of the operator.

9. In a buttonhole sewing machine, the combination with stitch-forming mechanism including a rotary turret, of work-holding means including work clamps, said work-holding means and stitch-forming mechanism having a relative movement, a main cam for producing such relative movement, which main cam makes one rotation during each buttonhole-forming cycle, a buttonhole cutter, means actuated by the main cam at a predetermined point in its rotation to actuate said cutter, means rendered operative by such relative movement to bring the cam to rest just before the main cam reaches its cutter-actuating position, other means actuated by the turret-rotating means to bring the cam to rest just after the main cam has reached cutter-actuating position, and means where-

by either of the two last-named means may be rendered operative at the will of the operator.

10. In a buttonhole sewing machine, the combination with stitch-forming mechanism including a rotary turret, of work-holding means including work clamps, a toggle device which when straightened closes the clamps and when broken opens the clamps, 5 said stitch-forming mechanism and work-holding means having a relative movement, a buttonhole cutter, a main cam which makes one complete rotation during each buttonhole-forming cycle and which produces said 10 relative movement, means actuated by the main cam at a predetermined point in its rotation to operate the cutter, turret-rotating means also operated by the main cam, means rendered operative by said relative movement 15 to break said toggle device just before the main cam reaches its buttonhole cutting position, other means actuated by the turret-rotating means to break said toggle just after the cam reaches its buttonhole cutting position, means to render either of said toggle-breaking means operative at the will of the operator, and means actuated by the releasing of the clamps to bring the cam to rest. 20
15. In a buttonhole sewing machine, the combination with stitch-forming mechanism, 25 relative movement, means actuated by the main cam at a predetermined point in its rotation to operate the cutter, turret-rotating means also operated by the main cam, means rendered operative by said relative movement to break said toggle device just before the main cam reaches its buttonhole cutting position, other means actuated by the turret-rotating means to break said toggle just after the cam reaches its buttonhole cutting position, and means to render either of said 30 toggle-breaking means operative at the will of the operator. 25
20. In a buttonhole sewing machine, the combination with stitch-forming mechanism including a rotary turret, of work-holding means including work clamps, said work-holding means and stitch-forming mechanism having a relative movement, a main cam for producing such relative movement, 35 which main cam makes one rotation during each buttonhole-forming cycle, a buttonhole cutter, means actuated by the main cam at a predetermined point in its rotation to actuate said cutter, means rendered operative by 40 such relative movement to bring the cam to rest just before the main cam reaches its cutter-actuating position, other means actuated by the turret-rotating means to bring the cam to rest just after the main cam has 45 reached cutter-actuating position, means whereby either of the two last-named means may be rendered operative at the will of the operator, and means actuated by the releasing of the clamps to bring the cam to rest. 50

12. In a buttonhole sewing machine, the combination with stitch-forming mechanism including a rotary turret, of work-holding means including work clamps, a toggle device which when straightened closes the clamps, 55 and when broken opens the clamps, said stitch-forming mechanism and work-holding means having a relative movement, a buttonhole cutter, a main cam which makes one complete rotation during each buttonhole-forming cycle and which produces said relative movement, means actuated by the main cam at a predetermined point in its rotation to operate the cutter, turret-rotating means also operated by the main cam, means rendered operative by said relative movement 60

to break said toggle device just before the main cam reaches its buttonhole cutting position, other means actuated by the turret-rotating means to break said toggle just after the cam reaches its buttonhole cutting position, means to render either of said toggle-breaking means operative at the will of the operator, and means actuated by the releasing of the clamps to bring the cam to rest. 70

13. In a buttonhole sewing machine, the combination with stitch-forming mechanism, of buttonhole-cutting mechanism, a main cam for actuating the buttonhole-cutting mechanism and controlling the point in the buttonhole-forming cycle at which the stitch-forming mechanism is actuated, and means to bring the machine to rest with the cam either in a position in which it is about to actuate the buttonhole-cutting mechanism or has just actuated it. 75

14. In a buttonhole sewing machine, the combination with stitch-forming mechanism, of buttonhole-cutting mechanism, work clamps, a main cam for actuating the buttonhole-cutting mechanism and controlling the point in the buttonhole-forming cycle at which the stitch-forming mechanism is actuated, means to bring the machine to rest with the cam either in a position in which it is about to actuate the buttonhole-cutting mechanism or has just actuated it, and means for invariably opening the work clamps at a point in each buttonhole-forming cycle subsequent to both the stitching and buttonhole-cutting operations. 80

15. In a buttonhole sewing machine, the combination with stitch-forming mechanism, of buttonhole-cutting mechanism, work clamps, a main cam which rotates once during each buttonhole-forming cycle, the stitch-forming mechanism being operated during a part of each rotation, a cam projection on the main cam for actuating the buttonhole-cutting mechanism, means for causing said cam projection to operate the buttonhole-cutting mechanism either before or after the stitching operation, and means for ensuring the opening of the work clamps during any buttonhole-forming cycle subsequent to both the stitching and buttonhole-cutting operations. 85

In testimony whereof, I have signed my name to this specification.

JOHN KIEWICZ.
